[57] CLAIM

The ornamental design for aeroponic plant grower housing
cover with seed support screens, as shown and described.

DESCRIPTION

FIG. 1 is a front perspective view of aeroponic plant grower
housing cover with seed support screens showing my
design;
FIG. 2 is a left side view thereof, the right side view being
a mirror image;
FIG. 3 is a front elevation view thereof;
FIG. 4 is a top plan view thereof;
FIG. 5 is a bottom plan view thereof; and,
FIG. 6 is a rear elevation view thereof.
